[57] CLAIM

The ornamental design for a foot warming pillow, as shown and described.

DESCRIPTION

FIG. 1 is a top plan view of a foot warming pillow showing our new design;

FIG. 2 is a front elevational view thereof;

FIG. 3 is a bottom plan view thereof;

FIG. 4 is a rear elevational view thereof;

FIG. 5 is a right side elevational view thereof, the left side being a mirror image of that shown;

FIG. 6 is a top plan view of a foot warming pillow showing a second embodiment of our new design;

FIG. 7 is a front elevational view of the foot warming pillow shown in FIG. 6;

FIG. 8 is a bottom plan view of the foot warming pillow shown in FIG. 6;

FIG. 9 is a rear elevational view of the foot warming pillow shown in FIG. 6;

FIG. 10 is a right side elevational view of the foot warming pillow shown in FIG. 6, the left side being a mirror image of that shown;

FIG. 11 is a top plan view of the foot warming pillow showing a third embodiment of our new design;

FIG. 12 is a front elevational view of the foot warming pillow shown in FIG. 11;

FIG. 13 is a bottom plan view of the foot warming pillow shown in FIG. 11;

FIG. 14 is a rear elevational view of the foot warming pillow shown in FIG. 11; and,

FIG. 15 is a right side elevational view of the foot warming pillow shown in FIG. 11, the left side being a mirror image of that shown.
